UNITED STATES PATENT OFFICE.

CHARLES HORTON, OF RIDGEFIELD PARK, NEW JERSEY, ASSIGNOR TO DUBILIER
CONDENSER & RADIO CORPORATION, OF NEW YORK, N. Y., A CORPORATION OF
DELAWARE.

RADICCONDENSER.

Application filed September 3, 1924. Serial No. 735,562.

To all whom it may concern:

Be it known that I, CHARLES HORTON, a citizen of the United States, residing at Ridgefield Park, in the county of Bergen and State of New Jersey, have invented 5 certain new and useful improvements in Radiocondensers, of which the following is a specification.

This invention relates to fixed condensers, 10 particularly to that type of fixed condenser suitable for radio reception.

A well-known condenser consists of a series of thin dielectric sheets interleaved with sheets of a conductive material, such 15 as copper or tin foil. The condenser stack as thus formed is enclosed between two insulating covers and the whole structure fastened together at opposite ends by metallic U-shaped clips having openings therein for 20 the passage of rivets. Usually a lug is attached to each U-shaped clip and the rivets fastened over the clips and the lugs, for greater ease in connecting the condenser to an electric circuit.

25 Frequently when the U-shaped clips are forced over the ends of the condenser stack and the insulating covers, the foil sheets, which project and are folded down against the outer face of one of the covers, are more 30 or less injured by the scraping action of the clip as it is being moved into position. Sometimes the foil sheets are so badly torn as to require the scrapping of the impaired condenser without any appreciable salvage 35 of the parts thereof.

A second trouble is encountered when a lug is placed on top of each clip and held in position by the operator while a rivet is inserted therethrough, preparatory to securing 40 the whole condenser assembly together. In this step the operator has three parts to assemble; the condenser, the lug and the rivet, and the operation consumes considerable time.

45 Among the objects of the invention, are to provide a new form of clip for enclosing the opposite ends of the assembled condenser pack, to render more perfect the contact between itself and the foil conductors which 50 project from the stack, and facilitate a rapid assembly of the condenser without inflicting damage or lessening the efficiency of the assembled device.

This invention aims more particularly to

provide an improved form of clip which 55 shall make a better and more complete surface contact with the conductive sheets in the condenser with a view to materially diminishing the losses accompanying the use of high frequency currents.

60 It is further contemplated to provide these clips with bent over portions for the protection of the foil sheets where the latter sheets are exposed.

65 Another object of the invention is to provide a clip which shall have associated therewith any one of a variety of lugs for attaching the assembled condenser to the other devices in the circuit, thereby decreasing the 70 number of parts necessary to produce a serviceable condenser.

75 It is further contemplated to provide a clip which shall have the necessary U-shaped formation to enclose the condenser, only when the two parts of which it is formed are brought together on the assembled condenser. This feature obviates the necessity of providing several types of clips of different sizes, to accommodate the various 80 thicknesses of the condensers of different capacity, in present day use.

Still more, it is aimed to provide a clip 85 which may be formed bow-shaped in part, so as to exert a pressure upon the entire condenser when completed. This result tends to reduce the air pockets in the condenser and also to eliminate loose connections which cause considerable loss of efficiency in 90 condensers.

95 A final object is indicated in the provision of a compound clip of the type which may be assembled with the usual rivet in position in one part of the same before the clip is put on the condenser, thus making possible expeditious performance of the final step in the assembling of the condensers by automatic or semi-automatic machinery.

100 These and other objects and advantages will appear from the subjoined detailed description of the embodiments of the invention illustrated in the accompanying drawings, in which:

Figure 1 is a perspective view of a form 105 of the clip on a condenser;

Figure 2 is a plan view of a condenser with a clip having a different configuration of the lugs thereon;

Figure 3 is an edge view of the clip shown

in Figure 2; the condenser bearing it being in side view;

Figure 4 is a side elevation of the clip and end view of the condenser shown in Figure 2;

Figure 5 is a detail side view of the upper section of the clip shown in Figure 2;

Figure 6 is a plan view of still another type of condenser and clip with a different configuration of the connecting lugs thereof;

Figure 7 is a side view of the clip shown in Figure 6, the condenser being in end elevation;

Figure 8 is a plan view of a still further modification of the clip, in which two lugs of different configuration are connected integrally each with one section of the clip; the condenser being in top plan;

Figure 9 is a front elevation of the clip shown in Figure 8; and

Figure 10 is a perspective view of a modified clip adapted for making connections with the other members of the circuit and also with a resistance of the tubular type as a grid leak; the condenser being seen from one end.

The same characters denote the same parts wherever they are shown.

The condenser is built up of dielectric layers 1, such as mica sheets, alternating with thin layers of conductive material 2, such as tin or copper. As is clearly shown in Figure 1 the sheets of conductive material project beyond the ends of the dielectric material as at 3, and usually are narrower than said dielectric sheets, as shown at 4. The assembled dielectric and foil layers are enclosed between covers 5 of insulating material, as bakelite, to furnish the required stiffness and backing for the layers therebetween. The complete stack or body of the condenser may be regarded as including not only the layers 2 and dielectric 3, but also the covers 5.

As shown clearly in Figures 1 and 3, the conductive sheets of foil which project from between the layers of dielectric material are folded over upon one face of one of the insulating covers at each end of same, as at 6, being held in position by the pressure produced by the clips 7.

The clips 7 which form the main feature of the invention herein disclosed are composed of two independent sections 8 and 9; which, when united by the passage of a rivet, such as an eyelet 10 therethrough, combine to form a substantially U-shaped clip, (see Figs. 1, 2 and 3). It is also to be understood that the shape of the condenser pack need not be as shown, since the clip sections may be constructed to suit any configuration of condenser.

As indicated in Figure 1 the sections 8 and 9 are made of substantially angle-shaped flat plates, each consisting of a por-

tion 11 bent to engage the end of the condenser stack, and a portion 12 to be in contact with the outside surface of one cover 5. By this arrangement, the sections when placed in inverse relationship upon one end or side of the condenser stack, will form a U-shaped clip, or clip of other shape corresponding to the form of the condenser.

Upon each lower section 8, with reference to Figure 1, there is integrally formed a connecting lug 13 which can be of any desired outline to allow for the proper location and connection of the condenser to the apparatus with which it is to be utilized. This lug may be bent into any angularly offset position in order to allow the utmost convenience in connecting the condenser in circuit.

As shown in Figure 1, each lug 13 which has an opening 13^a therein, is substantially parallel to the plane of the insulating cover 5 and the surface 12 of the clamp section 8.

The two sections 8 both have their portions 12 in contact with one and the same cover 5, and the sections 9 have their portions 12 in contact with the other cover 5. As the sections are disposed on the stack, the lugs 13 are adjacent diagonally opposite corners of the stack; and so are the portions 11 of the two sections 8 and the portions 11 of the two sections 9.

In the modification shown in Figures 3 and 4 inclusive, each section 8 of the clips at the opposite ends of the condenser has an upstanding arm or lug 14, in a plane perpendicular to the plane of the adjacent cover 5, to permit an ordinary grid, such as for the connection of a tubular leak, to be mounted on the condenser. The lugs 14 are connected to the portions 11 by portions 15, and extend obliquely, as at 16 and 17, towards the middle of the condenser so as to locate the contact openings 14^a in the lugs 16 and 17 at the opposite ends of a straight line along the center of the condenser, above the rivets 10.

The structure shown in Figures 6 and 7 illustrates a further modification of the arrangement of the sections 8 and 9 whereby a lug 18 protruding at right angles from each section 8, at the opposite ends of the condenser, is located substantially at the center of the clamp 7. This necessitates a change in the configuration of the sections 8 and 9 so that the portion 11^a is narrower and the portion 11^b of the section 8 is relatively wider; and the arms or lugs being united to the portions 11^b. The difference in the width of the respective sections however, does not in any way affect the utility or efficiency of the clip, since the two sections 8 and 9 when assembled will form a tight clip for enclosing the opposite ends of the condenser stack.

In Figures 8 and 9 another form of clip

is shown wherein the lugs 19 and 20 protrude from the same side of the condenser, both lugs being connected by the portions 21 from the condenser stack to the ends of the portions 12 of the sections 8, engaging the same cover 5. In this arrangement each section 8 is similar to that shown in Figures 1 to 4 inclusive, the only variance being indicated in the location of the lugs 19 and 20 on the sections 9 of the clip.

The lugs 19 and 20 on one side of the condenser make possible connection to apparatus that requires the two terminals of the condenser to be on the same side. It might be further noted that the slots 22 in the lugs 19 and 20 make possible a range of adjustability for the connections of the terminals of the condenser to the other devices.

Figure 5 illustrates a bend 23 in the portion 12 of each section of the clip to cause well defined pressure throughout the entire condenser and to prevent losses due to air pockets, which greatly lower the efficiency of the condenser.

In Figure 10, there is shown a further modification of the section 8 which has a lug 24 supplementing a lug 25, the supplementary lug 24 having an adjustment slot 30, while the lug 25 has the aperture 13^a only. By this arrangement varied connections may be made; as for instance, the attachment of the condenser to a transformer and the simultaneous use of a grid leak resistance.

In this above described arrangement of sectional clips the separate operation of positioning the eyelets 10 is obviated. The eyelet may be inserted in one section, as the section 9, before the eyelet is inserted in the condenser. When the section 9 is placed on the end of the stack, and the section 8 is placed in proper relation thereto, it is only necessary to exert pressure to expand the ends of the rivets 10, thus securing the sections to the stack and completing the condenser.

It is understood, of course, that the sheets 1 and 2, and the covers 5 are perforated to allow the rivets to pass through the stack, and hold the sections 8 and 9 on the opposite faces thereof. Part of the conductive sheets 2 must make contact with the clip at one end of the condenser and the remaining sheets must make contact with the clip at the other end, and the rivet holding one clip will be out of contact with the sheets 2 whose projecting ends 6 will be in contact with and engaged by the other clip, as by making openings through the sheets 2 in contact with the other clip larger than the diameter of the rivet, as is well known to those skilled in this art.

It should be further understood that inasmuch as each clip 7 is formed of two sections 8 and 9, that the present difficulty en-

countered when integral U-shaped clips are forced over the ends of the condenser stack, whereby the projecting ends 6 of the foils 2 are usually torn or crimped due to the force required to push the tight fitting one-piece U-shaped clip over the end of the stack, is completely obviated. In the clip 7 illustrated in this application, the sections 8 and 9 are merely placed upon opposite faces of the condenser stack, the foil ends 6 being covered without any tearing or crimping. When the eyelets have been riveted, the compression is permanent due to the pressure applied by the bend 23 and the U-shaped configuration of the clip including the integral lug for connecting purposes is permanently obtained.

It is of course obvious that various changes and modifications may be made to the details of construction above described without departing from the spirit of this invention as set forth in the appended claims.

I claim as my invention:—

1. An electrical condenser comprising a stack having clips thereon, each clip including separate sections secured to the stack, one section of each clip directly engaging only one of the faces of the stack and having a portion bent over only the adjacent side of said stack, and the other section directly engaging only the opposite face of the stack and having a portion bent over only the same side thereof.

2. An electrical condenser comprising a stack having clips thereon, each clip including separate sections secured to the stack, one section of each clip directly engaging only one of the faces of the stack and having a portion bent over only the adjacent side of said stack, and the other section directly engaging only the opposite face of the stack and having a portion bent over only the same side thereof, said bent portion of each section being relatively smaller than the remainder of said section.

3. An electrical condenser comprising a stack having clips thereon, each clip including separate sections affixed to the stack, one section of each clip directly engaging only one of the faces of the stack, and the other section directly engaging only the opposite face thereof, at least one section of each clip having a portion bent with respect to the remainder of the section over only the adjacent side of the stack.

4. An electrical condenser comprising a stack having clips thereon, each clip including separate sections affixed to the stack, one section of each clip directly engaging only one of the faces of the stack, and the other section directly engaging only the opposite face thereof, at least one section of each clip having a portion bent with respect to the remainder of the section over only the adjacent side of the stack.

cent side of the stack, each of said bent portions being relatively smaller than the remainder of the sections associated therewith.

5. An electrical condenser comprising a stack having clips thereon, each clip including separate sections, one section of each clip having a portion directly engaging only one of the faces of the stack and having another portion bent over only the adjacent 10 side of said stack, the other section having a similar portion directly engaging only the opposite face of the stack and having another portion bent over only the same side thereof, said bent portions of each clip being smaller than the first-named portion and 15 being disposed adjacent each other.

6. An electrical condenser comprising a stack having clips thereon, each clip including separate sections, one section of each clip 20 having a portion directly engaging only one of the faces of the stack and having another portion bent over only the adjacent side of

said stack, the other section having a similar portion directly engaging only the opposite face of the stack and having another portion 25 bent over only the same side thereof, one of the bent over portions of each clip of the condenser having a connecting lug projecting therefrom.

7. An electrical condenser comprising a 30 stack having clips thereon, each clip including sections, each section of each clip having a portion directly engaging only one face of the stack, and each section of each clip also having a portion bent to extend over only 35 one and the same side of the stack, the bent over portion being relatively small and the first-named portion having a bend therein intermediate its ends; and means to secure the clips to the stack and press the first-named portions thereof flat against the outer faces thereof.

In testimony whereof I affix my signature.
CHARLES HORTON.
